UNITED STATES PATENT OFFICE.

HARRY DUBBS, OF FREDERICKSBURG, PENNSYLVANIA.

SKIRT-HOLDER.

1,049,062.

Specification of Letters Patent.

Patented Dec. 31, 1912.

Application filed November 22, 1911. Serial No. 661,777.

To all whom it may concern:

Be it known that I, HARRY DUBBS, a citizen of the United States, residing at Fredericksburg, in the county of Lebanon and 5 State of Pennsylvania, have invented new and useful Improvements in Skirt-Holders, of which the following is a specification.

The invention relates to a skirt holder and adjuster and has for its primary object 10 to provide a device of this character in which a skirt may be raised the desired height and held in such position so as to prevent the same dragging when being worn and also to avoid the necessity of holding the said skirt lifted by the hands of the 15 wearer, thus giving free use of the hands of such wearer.

Another object of the invention is the provision of a skirt holder in which a skirt may 20 be raised the desired height and held fastened, thereby avoiding the necessity of attention thereto by the user as well as obviating lifting of the skirt by hand.

A further object of the invention is the 25 provision of a skirt holder which when applied to the skirt is neat in appearance, simple in construction, reliable and efficient in its purpose and inexpensive in manufacture.

With these and other objects in view the 30 invention consists in the construction, combination and arrangement of parts, as will be hereinafter more fully described in detail, illustrated in the accompanying drawing and pointed out in the claim hereunto 35 appended.

In the drawings:—Figure 1 is a rear elevation of a skirt showing the invention applied thereto, the same being partly shown in dotted lines; Fig. 2 is a fragmentary plan 40 view of the skirt looking toward the inner side thereof showing the application of the device. Fig. 3 is a perspective view of the clasp or fastener clip.

Similar reference characters indicate corresponding parts throughout the several 45 views of the drawing.

Referring to the drawings by numerals, 5 designates generally a skirt which is made in the ordinary well known manner and on

which is mounted the skirt holder, presently 50 described.

The skirt holder comprises a main pull cord 6 formed at one end with a plurality of branches 7, the same being stitched or otherwise secured at spaced points with respect to each other to the skirt preferably at the rear thereof, while the opposite end of the main cord 6 is passed through an ordinary eyelet 8 in this instance two of such eyelets are shown fastened in the skirt contiguous to the waist band 9 thereof and at the hip portions of the said skirt so that the cord may be trained through either of these eyelets should it be desired, the outer end of the main cord 6 being provided with a tassel 10 for ornamenting the same. Adapted to be secured to the skirt 5 adjacent to either of the said eyelets 8 is a clip comprising a pair of pivotally connected jaws 11 one of which being fixed to the skirt 5, 70 the jaws being closed by means of a spring 12 supported by the pivot 13 connecting the jaws. The jaws are formed with inturned ends 14 overlapping each other, one of the said ends being formed with a guide eye 15 75 through which is trained the main cord 6, the latter being also trained through a guide eye 16 in the outermost jaw of the clip, it being seen that the inturned end 14 of the other jaw will pinch the cord or grip the 80 same so as to hold it in adjusted position. Upon pulling upon the cord 6 the skirt may be raised the desired height and to accomplish this the clip is opened permitting the cord to freely slip through the clip and upon 85 closing thereof said cord will be gripped thereby holding the same in adjusted position, and thus sustaining the skirt raised.

From the foregoing it is thought that the construction and operation of the invention 90 will be apparent, and therefore, a more extended explanation has been omitted.

What is claimed is:

The combination with a skirt having spaced eyelets mounted therein near the 95 waist band of the same and on opposite sides of and spaced from the placket therein, of a skirt lifter comprising a cord hav-

ing one end connected to the inner face of
the skirt at a point considerably below the
point of mounting of the eyelets, and adapt-
ed to be trained through either of the same,
5 a pair of branch cords connected to the first
named cord intermediate the ends thereof
and having their ends connected at spaced
points of the skirt and means on the outer

side of the skirt for fastening the first
named cord when adjusted. 10

In testimony whereof I affix my signature
in presence of two witnesses.

HARRY DUBBS.
